UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPGRAPHICAL MACHINE.

1,137,981.

Specification of Letters Patent.

Patented May 4, 1915.

Application filed June 19, 1914. Serial No. 846,021.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

- 10 My invention relates to typographical machines, such as linotype machines of the general organization represented in Letters Patent of the United States, No. 436,532, to O. Mergenthaler, wherein circulating matrices 15 are released from a magazine in the order in which their characters are to appear in print and then assembled in line, the composed line transferred to the face of a mold, the mold filled with molten metal to form a 20 slug or linotype against the matrices which produce the type characters thereon, and the matrices thereafter returned through distributing mechanism to the magazine from which they started.
- 25 More particularly, it relates to that kind thereof equipped with a plurality of shiftable magazines and coöperating means, whereby any selected one may be brought into operative position at will.
- 30 In the accompanying drawings, I have shown my improvements as adapted to a style of machine somewhat similar to that disclosed in the application for Letters Patent of Pearce and Billington, filed January 27, 1914, Serial No. 814,670. However, it 35 will be understood that many changes and variations may be made therein, and in their mode of adaptation, which will still be comprised within the spirit of the invention;
- 40 and that they may be applied to other forms of typographical machines, such as typesetters, typecasters and the like, which handle type or dies, instead of matrices.

Generally speaking, I desire it to be understood that I do not limit myself to any specific form or embodiment, except in so far as such limitations are specified in the claims.

Referring to the drawings: Figure 1 is a 50 side view, partly in section and broken

away, of a portion of the machine; Fig. 2 is a section on the line 2—2 of Fig. 1; Fig. 3 is a view somewhat similar to Fig. 1, but showing the parts in different position; Fig. 4 is a detail section on the line 4—4 of Fig. 55 5; Fig. 5 is an enlarged vertical section through the lower ends of the magazines, etc.; and Fig. 6 is an enlarged perspective illustrating the keyboard shift.

The matrices X are stored according to 60 font in the superposed magazines A¹, A², A³, A⁴, four such magazines being shown in the drawings for purposes of illustration, although it will be understood that my invention is equally applicable to a different number thereof. As in the Pearce and Billington application, the magazines may be shifted so as to bring selected pairs thereof simultaneously into operative relation to the assembling devices, it being noted, however, 65 that in the present instance any two adjacent magazines may be thus employed, as distinguished from the more limited capability of selection in said application. Thus, Fig. 1 illustrates the uppermost pair of magazines 70 A¹ and A² in action; while Fig. 3 shows the middle pair A³ and A⁴ in operative position.

The superposed magazines are suitably connected, and their shifting means preferably comprise the four cams C, mounted respectively at the ends of two transverse shafts C¹, beneath the lowermost magazine and supporting the entire series, the forward pair of cams being located at or near the front end of the magazines and the other 80 pair of cams at or near their rear end. The means for operating the cams C comprise the fore-and-aft shaft D connected by bevel gearing D¹ to the two shafts C¹, and provided at its forward end with the operating handle E, whereby the magazines may be raised or lowered as desired. In order to lock the magazines in their adjusted position, the handle E (Fig. 1) is movable longitudinally upon the shaft D, and is arranged to engage 85 normally with the stop or stud E² upon the fixed frame, a spring E¹ tending to return the handle to its normal or locked position. When it is desired to shift the magazines, the handle is moved forwardly and the shaft 90

D rotated thereby, and after the magazines are brought to the desired level, the spring E¹ acts to engage the handle with the stop E², whereby the parts are secured against accidental displacement.

As previously stated, any contiguous pair of magazines may be brought into operative relation to the assembling devices, and to this end, the raceway B is formed with two throats, one B¹ to register with the upper magazine, and the other B² to register with the lower one. As the matrices X are released from either of the active magazines, they pass through their respective throats into the raceway B to the belt B³, whereby they are conveyed to the other assembling devices, all in the manner well understood in the art.

Each of the magazines is provided with its own series of escapements to control the delivery of the matrices therefrom, the respective escapements being all located beneath or at the lower side of the magazines, this arrangement being unlike that in the Pearce and Billington construction, where in some of the magazines are provided with escapements on their upper sides. The escapements are of the usual form, and each consists of the pivoted lever F, pawls F¹ and F², and the spring F³ tending to move the lever in one direction. The actuating devices for the escapements are mounted upon the stationary framework, and are so located that the magazines and their connected escapements may be shifted with reference thereto without hindrance or obstruction.

The actuating means for the escapements of the upper active magazine comprise (Fig. 4) the series of pivoted levers G, located beneath the throat B¹, the normal position of these levers being indicated by dotted lines, at which time they are out of engagement with the escapement levers F, and also out of the path of the magazines. Mounted in proximity to each of the levers G is a link G¹, slidably mounted in the framework, as for instance by the pin-and-slot connection J¹ at its upper end, and the rolls J (Fig. 4) at its lower end. The link G¹ is formed with an arm G² projecting into position to engage the lever G, so that as the link is elevated, the lever is swung about its pivot into engagement with and so as to operate the escapement. The means for operating the escapements of the lower magazine are somewhat similar, and comprise the levers H located beneath the throat B² and the links H¹ pivoted thereto.

The lower ends of the links G¹ and H¹ (Figs. 5 and 6) rest respectively upon the vertically movable reeds G³ and H³, suitably mounted in the frame, and arranged in parallel and staggered relation to each other. At the lower ends of these reeds is

a series of vertically movable slides K, of sufficient width to engage either set of reeds according to the lateral position of the latter. The means for moving the slides K may be of any well-known or desired construction, as for instance, the ordinary keyboard mechanism K¹ controlled by finger keys K², as shown in Fig. 1.

As best shown in Fig. 6, the relation of the slides K to the two staggered series of reeds G³ and H³ is such that when one set of reeds is engaged thereby, the reeds of the other set will be located in inactive position between the slides. At this time, the operation of the keys K² will effect the actuation of the escapements corresponding to the engaged set of reeds. In order to permit the delivery of matrices from the other magazine, it is necessary to disengage the active set of reeds from the slides K, and to engage the other set therewith. This I preferably effect by the two manually controlled slides L and L¹, the former engaging the reeds G³, and the latter the reeds H³. These slides are connected at their ends to the centrally pivoted lever M provided with the handle M¹, in such manner that the movement of the lever effects the shifting of the slides in opposite directions; that is to say, in one position of the handle, the reeds H³ are in operative relation to the slides K, and in its other position the reeds G³ are in operative relation to the slides. The operator may thus at will deliver matrices from either of the pair of magazines in operative position. A suitably marked plate N, in proximity to the handle M¹, serves to indicate which set of escapements is in action.

It is pointed out that in the Pearce and Billington construction, due to the location of the escapements on the top side of certain of the magazines, the actuating links for such escapements extend upwardly between the paths of the matrices passing from the magazines, which arrangement necessitates an allowance for clearance, and thus restricts to some extent the width or thickness of the matrices stored in the magazines. In my improved construction, due to the location of all the escapements at the bottom of the magazines, the escapements of the upper magazine of the active pair are actuated by links which do not pass between its matrix paths, and hence it is feasible to store thicker or wider matrices therein than would otherwise be possible. This feature is of considerable importance, in that it permits the employment of head-letters, display characters, etc. in combination with the smaller and more frequently employed fonts.

As previously stated, I have illustrated my invention only in preferred form and by way of example; but obviously many modifications and alterations therein, and in its mode of application, will suggest

themselves to those skilled in the art, without departure from its scope.

Having thus described my invention, its construction and mode of operation, what I claim and desire to secure by Letters Patent of the United States, is as follows:

1. In a typographical machine, the combination of two superposed magazines each provided with a series of escapements, and two series of actuating devices, one for each series of escapements, the actuating devices for the upper magazine extending across the mouth of the lower magazine and through which the type or matrices therefrom pass, and the escapements of the upper magazine being located on its under side so that their actuating devices will stand out of the path of the type or matrices passing therefrom. 10
2. In a typographical machine, the combination of two superposed magazines, each provided with a series of escapements, and two series of actuating devices mounted exteriorly of the magazines, one for each series of escapements, the actuating devices for the upper magazine extending past the mouth of the lower magazine and through which the type or matrices therefrom pass, and the escapements for both magazines being located on their under sides so that their corresponding actuating devices will stand out of the path of the outgoing type or matrices. 20
3. In a typographical machine, the combination of a plurality of superposed magazines movable to bring different selected pairs thereof into operative position, and each provided with a series of escapements, and two series of actuating devices for the escapements of the selected magazines, the actuating devices for the upper one of said magazines being arranged so as to stand out of the path of the outgoing type or matrices. 30
4. In a typographical machine, the combination of a plurality of superposed magazines movable to bring different selected pairs thereof into operative position, and each provided with a series of escapements, and two series of actuating devices for the escapements of the selected magazines, the escapements for the upper one of said magazines being located on its under side so that their actuating devices will stand out of the path of the outgoing type or matrices. 40
5. In a typographical machine, the combination of a plurality of superposed magazines movable to bring different selected pairs thereof into operative position, and each provided with a series of escapements, and two series of actuating devices for the escapements of the selected magazines, the said escapements being located on the under side of all the magazines so that the actuating devices may coöperate with the escapements of any selected pair of adjoining magazines. 50
6. In a typographical machine, the combination of two magazines, each provided with a series of escapements on its under side and movable into and out of operative position, and two series of actuating devices for the escapements, the said actuating devices being supported independently of the magazines and arranged so as to permit their free and unimpeded relative movement. 60
7. In a typographical machine, the combination of two magazines each provided with a series of escapements on its under side and movable into and out of operative position, and two series of pivoted levers to engage directly with the escapements of the two magazines, the said levers being mounted independently of the magazines and arranged so as to permit their free and unimpeded relative movement. 70
8. In a typographical machine, the combination of two series of escapement actuating devices, a single series of operating members therefor, and means for shifting the two series of actuating devices relatively to each other to bring them alternately into operative relation to the operating members. 80
9. In a typographical machine, the combination of two magazines each having a series of escapements, two series of escapement actuating devices, a single series of operating members therefor, and means for shifting the actuating devices so as to locate those of one series above the operating members, and those of the other series between the said members, and vice versa. 90
10. In a typographical machine, the combination of a plurality of magazines each provided with a series of escapements on its under side and two series of actuating devices for the escapements, the said parts being arranged so that the actuating devices may be connected to the escapements of any selected pair of adjoining magazines. 100
11. In a typographical machine, the combination of a plurality of magazines movable to bring different selected pairs thereof into operative position, and each provided with a series of escapements on its under side, and two series of actuating devices for the escapements of the selected magazines. 110
12. In a typographical machine, the combination of a plurality of magazines movable to bring different selected pairs thereof into operative position, and each provided on its under side with a series of escapements, and two series of pivoted levers adapted to engage directly with the escapements of the selected magazines, the said levers being mounted independently of the magazines and arranged so as to permit their free and unimpeded movement. 115
13. In a typographical composing machine, the combination of a plurality of superposed inclined magazines, an escapement for each magazine, a common raceway adapted to receive matrices from all the 120
14. In a typographical machine, the combination of a plurality of inclined magazines, an escapement for each magazine, a common raceway adapted to receive matrices from all the 130

4
magazines, a plurality of throats adapted to conduct matrices released by the escapements from the respective magazines to the said common raceway, an escapement rod acting on the escapement of one magazine without traversing any of the throats, and an escapement rod acting on the escapement of another magazine and traversing a throat other than that appropriate to the matrices

descending from the last mentioned magazine.

In testimony whereof, I have affixed my signature in presence of two witnesses.

DAVID S. KENNEDY.
